UNITED STATES PATENT OFFICE.

WILLIAM FRANK ZIMMERMANN, OF WAVERLY, NEW YORK, ASSIGNEE TO INGERSOLL-RAND COMPANY, OF JERSEY CITY, NEW JERSEY, A CORPORATION OF NEW JERSEY.

EXHAUST DEFLECTOR.

Application filed July 15, 1925. Serial No. 43,705.

This invention relates to pneumatic hammer tools, but more particularly to the exhaust deflector disclosed in my co-pending application, Serial No. 18,656, filed March 5 27, 1925, for a pneumatic chipping hammer.

The objects of the present invention are to improve upon the means for deflecting the exhaust from pneumatic tools and enable the exhaust deflector to be located between the cylinder and handle of the machine, but in a convenient and protected position.

The invention is illustrated in one of its preferred forms in the accompanying drawings, in which—

Figure 1 is a side elevation partly broken away and in vertical section showing a chipping hammer provided with the exhaust deflector,

Figure 2 is a detail perspective view of the exhaust deflector, and

Figures 3 and 4 are diagrammatic longitudinal sectional views illustrating the operation of the machine.

Referring to the drawings, the cylinder or barrel A is formed with the bore B for the reciprocating hammer piston C having the neck D. Blows of impact are imparted to the chisel or tool E located at the front end of the cylinder. The rearward portion of the cylinder is provided with an enlarged bore F to receive the valve box G in the form of a hollow block, and also to receive the forward valve box cap H and the rearward valve box cap J. The handle K having the handle grip L is suitably secured to the barrel as by means of the bolts O. The handle grip contains the throttle valve (not shown) controlled by the latch 40 P for supplying pressure fluid to the machine.

The pressure fluid actuated distribution valve Q may be of any suitable type but is shown of the differential type and is located in the valve box G with its axis longitudinal. Pressure fluid is supplied to the machine from the supply passage R in the handle L and a main exhaust S is provided for the machine at a point located rearwardly of the valve. This main exhaust is conveniently located in the rearward valve box cap J and an exhaust deflector T is provided for this main exhaust between the handle and cylinder. The exhaust deflector T

as shown in Figure 2 is in the form of a split ring open at one side at 3 and the edges of the ring are preferably turned at an angle to form flanges 4, so that the ring is of trough shape for conducting the exhaust to atmosphere through the space or opening left between the cylinder and back head as indicated in Figure 1. A portion of one flange, preferably opposite the open portion 3, is cut to form a tongue 5 which cooperates with notches 8 in the barrel for holding the deflector in a given adjusted radial position on a portion of the valve box, with reference to the longitudinal axis of the cylinder. The deflector is securely positioned between the cylinder and handle and is protected and not subject to derangement or loss.

The radius of the fillet 6 of the counterbore of the handle K is greater than the radius of the corner 7 of the deflector T, so that when the handle is tightened to the barrel, the smaller radius 7 rides up on the fillet 6 and the deflector T is gripped and held in position by this means.

The supply of pressure fluid to both ends of the cylinder is controlled by the valve, and the main exhaust from the forward end of the cylinder through the exhaust passage U is controlled by the piston C, and in addition to this main exhaust an auxiliary exhaust is provided from the front end of the cylinder through the passage V controlled by the valve Q. The exhaust from the rear end of the cylinder through the port W passes through the valve Q itself to the main exhaust S and is controlled by the valve.

The valve is thrown forward and held in forward position by live fluid pressure acting upon the shoulder of the enlarged head of the valve, and the valve is thrown to rearward position and held in said position by live pressure fluid acting against the valve in a rearward direction and controlled by the neck D of the piston which cooperates with the passage X in the cylinder.

The differential valve Q which is one type of valve which has been successfully used is preferably formed with the enlarged head Y and the neck Z, and the valve has an open rearward end a. The enlarged head Y forms a rearward shoulder b on the valve

having a forwardly acting pressure surface and the pressure of the live fluid upon this surface *b* actuates the valve forwardly and holds the valve in forward position as indicated in Figure 3, for instance, because the pressure fluid supplied through the passage *R* in the handle passes directly to the valve around the neck *Z*, and from thence to the rearward end of the cylinder through the ports and passages indicated for driving the piston forwardly. The rearwardly acting pressure surface *c* of the enlarged head of the valve is subjected to atmospheric pressure when the valve is in its forward position as indicated in Figure 3 through the passage *X* and the exhaust passage *U* and the passage *V*. When live pressure fluid is supplied through the passage *T'* in the cylinder and around the neck *D* of the piston and through the passage *X* to the rearwardly acting pressure surface *c* of the valve as indicated in Figure 4, the valve will be actuated rearwardly and held in rearward position owing to the fact that the area *c* is larger than the area *b*.

In the operation of the chipping hammer, let it be assumed that the piston is in its rearmost position as indicated in Figure 3 and the valve is in its forward position in which case live pressure fluid admitted from the passage *R* in the handle will pass through the rearward valve box cap *J* and through passages in the valve box around the neck *Z* of the valve and through a passage in the forward valve box cap and the port *W* to the rearward end of the cylinder which will drive the piston forward. At the time that the edge *d* at the front end of the piston covers the port *e* of the passage *X*, the edge *f* of the neck *D* will have uncovered the port *g* of the live pressure fluid supply passage *T'* so that pressure fluid will flow around the neck *D* of the piston and through the port *h* in the side of the cylinder communicating with the passage *X* leading to the forward end of the valve so that the valve is then thrown rearwardly due to the differential areas of the valve.

As the valve is thrown rearwardly, live pressure fluid is supplied from the supply passage *R* in the handle around the neck *Z* of the valve and through the supply passage *V* to the front end of the cylinder. The piston, however, has sufficient momentum to strike its blow upon the chisel shank *E* and commences its rearward motion before the pressure begins to build up in front of the piston to drive it rearwardly. This position of the parts is shown in Figure 4. The rearward motion of the piston is due both to rebound and to live pressure fluid admitted as described.

During the rearward travel of the piston when the edge *d* at the forward end of the piston uncovers the port *e* of the passage *X*

and the port *j* of the exhaust passage *U*, the edge *f* of the piston neck will have covered the ports *g* and *h* thus closing off the supply of live pressure fluid to the rearwardly acting pressure surface *c* of the valve and the forward end of the valve will thus be open to exhaust through the passage *X* and the exhaust passage *U*. At this time the live pressure fluid on the forwardly acting pressure surface *b* of the valve head or shoulder will throw the valve forwardly to the position indicated in Figure 3 and open the auxiliary exhaust for the front end of the cylinder through the passage *V* and over the rearward end of the valve to the main exhaust *S*. Before this occurs, however, the exhaust from the rearward end of the cylinder as the piston is traveling rearwardly passes out through the port *W* and through the ports *h* and *o* in the valve head and through the valve itself to the main exhaust *S*.

The pressure fluid trapped in the rearward end of the cylinder after the valve has shifted to its forward position but while the piston is moving rearwardly forms a cushion so that the piston is not stopped abruptly and due to its cushion reverses its movement without reversal of the movement of the valve. From this point the cycle is repeated.

I claim:—

1. In a pneumatic hammer tool, the combination of a cylinder and reciprocating piston, a handle having a filleted counterbore, means for connecting the handle to the cylinder, an exhaust deflector in said counterbore in the form of a split ring open at one side, the edges of the ring being bent inwardly at an angle, the radius of the fillet of the counterbore being greater than the radius of the bend of the cooperating corner of the deflector, whereby the deflector is gripped tightly in the counterbore when the handle is tightened to the cylinder.

2. In a pneumatic hammer tool, the combination of a cylinder and reciprocating piston, a handle having a filleted counterbore, means for connecting the handle to the cylinder, an exhaust deflector in said counterbore in the form of a split ring open at one side, the edges of the ring being bent inwardly at an angle, the radius of the fillet of the counterbore being greater than the radius of the bend of the cooperating corner of the deflector, whereby the deflector is gripped tightly in the counterbore when the handle is tightened to the cylinder, and cooperating means between the cylinder and the deflector for holding the deflector in different adjusted angular positions.

In testimony whereof I have signed this specification.

WILLIAM FRANK ZIMMERMANN.
